Primary Examiner—Alan P. Douglas*Assistant Examiner*—M. N. Pandozzi*Attorney, Agent, or Firm*—Kurt R. Benson[57] **CLAIM**

The ornamental design for a drinking container, as shown and described.

DESCRIPTION

FIG. 1 is a perspective view of a drinking container of the subject invention in a first position;

FIG. 2 is a top plan view thereof;

FIG. 3 is a bottom plan view thereof;

FIG. 4 is a right side elevational view thereof, the opposite side being a mirror image;

FIG. 5 is a front elevational view thereof;

FIG. 6 is a rear elevational view thereof;

FIG. 7 is a perspective view thereof in a second position;

FIG. 8 is a top plan view thereof in the second position;

FIG. 9 is a bottom plan view thereof;

FIG. 10 is a right side elevational view thereof in the second position, the opposite side being a mirror image;

FIG. 11 is a front elevational view thereof in the second position; and,

FIG. 12 is a rear elevational view thereof in the second position.

FIG. 1

FIG. 2

FIG. 3

FIG. 4
